United States Patent Office

Des. 196,581
Patented Oct. 15, 1963

196,581

MIRROR AND PICTURE HANGER

Joseph M. Margulis, ½ Jiffy Enterprises Inc.,
150 N. 13th St., Philadelphia, Pa.

Filed Oct. 5, 1962, Ser. No. 72,006

Term of patent 14 years

(Cl. D17—12)

FIG. 6

FIGURE 1 is a front elevation view of a mirror and picture hanger showing my new design;

FIGURE 2 is a right side elevation view thereof;

FIGURE 3 is a rear elevation view thereof;

FIGURE 4 is a top plan view thereof;

FIGURE 5 is a bottom plan view thereof; and

FIGURE 6 is a left side perspective view thereof.

I claim:

The ornamental design for a mirror and picture hanger, substantially as shown.

References Cited in the file of this patent

UNITED STATES PATENTS

D. 171,263 Newlin ----- Jan. 5, 1954